UNITED STATES PATENT OFFICE

ARCHIBALD HALL-BROWN, OF PURLEY, AND EDWIN WALTER JONES, OF LINCOLN, ENGLAND, ASSIGNEES TO THE BABCOCK & WILCOX COMPANY, OF BAYONNE, NEW JERSEY, A CORPORATION OF NEW JERSEY

AIRSHIP MOORING MEANS

Application filed April 19, 1929, Serial No. 356,409, and in Great Britain July 17, 1928.

This invention relates to airship mooring tower heads and more particularly to airship mooring tower heads having a swinging arm supported in a gimbal frame and having a telescopic portion which can be moved in or out by supply of a pressure medium.

The invention is concerned with the control of the movement of the swinging arm or the like and has for its object to provide control means which can be operated by a single attendant and from a central position.

In accordance with the invention, the valve gear is so arranged that by the operation of a single hand wheel or lever, valves are opened or closed in proper sequence to control the admission and exhaust of pressure fluid whereby to effect operation of the ram element of the swinging arm and also if desired locking means associated with said ram.

20 In conjunction with the valve gear there may be provided indicating means for indicating the corresponding movement at any time.

The invention is illustrated in the accompanying drawings, in which:—

25 Fig. 1 is a vertical section on the line 1—1 of Fig. 2 of the control valve.

Fig. 2 is a section on the line 2—2 of Fig. 1.

Fig. 3 is an elevation at right-angles to Fig. 1 looking in the direction indicated by the 30 arrow X (Fig. 1).

Figs. 4, 5 and 6 are detail views of the valve body drawn to a smaller scale showing the inlet and exhaust branches thereon.

Figs. 7, 8 and 9 are views showing the assembly of the control valve in conjunction with indicating devices.

Fig. 10 is a vertical sectional view through an airship mooring mast and its supporting means.

40 Referring first to Fig. 10 in which there is shown a mooring mast with which the invention may be used, the character A designates the mooring head adapted to receive a part of the airship to be secured thereto by means of the cable B running longitudinally through the arm C secured to the head. This arm C is in the form of a piston or ram reciprocating in the cylinder D mounted in gimbals, as shown, the movement of the arm 45 being controlled by means of fluid pressure

conducted to the cylinder through pipes E. The arm has a lower extension F which is adapted to be received in a movable piston G mounted in a cylinder H and adapted to engage the lower extremity of the extension F 55 on the arm to lock the same in position. The piston G is operated by fluid pressure supplied to the cylinder through the high and low pressure tanks J, the fluid being supplied to these tanks through pipes K.

The control of the fluid supplied to the cylinders D and H is preferably effectuated according to this invention by a single movable member which controls the various valves, in a manner which will now be described. The control valve proper shown comprises a body or chest 1 of which the rear end is subdivided into a set of compartments 2, 3, 4, 5, (Fig. 1) and a set of compartments 7, 8, 9, 10 separated therefrom by a vertical 60 partition 6.

The partition 6 is apertured on each side of a dividing rib 11 to present seatings for horizontally disposed valves 12—19 vertically spaced, four on each side of the rib 11, the valves 12—15 on one side of the rib 11 being arranged in staggered relation to the valves 16—19 on the other side of the rib.

The valves 12—15 are inlet valves, the valves 12, 13, 14 being adapted, respectively, to control the passage of pressure fluid from the compartment 7 to the compartments 2, 3, 4 and the valve 15 being adapted to control the passage of pressure fluid from the compartment 8 to the compartment 5.

The valves 16—19 are exhaust valves; the valves 16, 17, 18 being adapted, respectively, to control the passage of fluid from the compartments 2, 3, 4 to the compartment 9 and the valve 19 being adapted to control the passage of pressure fluid from the compartment 5 to the compartment 10.

The inlet compartment 7 is provided with a supply branch 20 connected to a source of fluid pressure supply; the compartment 9 is 85 provided with an exhaust branch 21; the compartment 8 is provided with a supply branch 22 connected to a source of pressure supply working at a lower pressure than that supplied to the branch 20, and the com- 100

partment 10 is provided with an exhaust branch 23.

The compartments 2, 3, 4, 5 are provided, respectively, with branches 24, 25, 26, 27 connected, respectively, to the bottom side of the locking piston, to the top side of the locking piston, to the top side of the ram element and to the bottom side of the ram element of the mooring head.

10 The valves 12-19 are guided for horizontal movement at 28 in the body 1 and are maintained in engagement with their seats by helical compression springs 29.

The valve-actuating means comprises a 15 vertical cam shaft 30 rotatably journaled in a casing 31 secured to the front of the body 1 and carrying suitably profiled cams 12', 13', 14', 15', 16', 17', 18', and 19', one for each valve 12-19, and each co-operating 20 with a rocker lever 32 carrying a tappet 33 engaging the relative valve stem.

The cam shaft 30 is manually rotatable by means comprising a handwheel 34 secured to a shaft 35 unitary with a worm 36 meshing 25 with a worm-wheel 37 keyed to the top end of the spindle 30, the shaft 35 and worm-wheel boss 38 being journaled in a casing 39 surmounting the casing 31.

30 The arrangement is such that by manual rotation of the handwheel 34 in clockwise direction the valves are opened and closed in proper sequence to operate the ram element of the mooring head and also to actuate the locking piston co-operating with said element.

35 It will be understood that the two upper valves 12, 16 constitute, respectively, the inlet and exhaust valves controlling the bottom side of the locking piston; the next pair 40 of valves 13, 17 controlling the top side of the ram element and the lower pair of valves 15, 19 controlling the bottom side of the ram element.

45 The compartments 8 and 10 are isolated from the compartments 7 and 9 because the fluid pressure supplied to the bottom side of the ram element is less than that supplied to the top side of said element and to the locking piston.

50 The control valve is designed to control the pressure fluid so that the following operations are performed successively:—

- (1) The pin which locks the ram element in central position is withdrawn.
- 55 (2) The ram element is protruded.
- (3) The ram element is retracted.
- (4) The locking means is operated to lock the ram element in central position.

50 It will be understood that, although the control valve is arranged for two pressures only, any number of pressures may be provided for by a suitable arrangement of partitions.

65 The handwheel shaft 35 is extended rearwardly and is operatively connected by gear-

ing indicated generally at 40 (Fig. 8) and a chain 41 to an indicator 42 of which the dial is marked as follows: "Neutral", "Unlock", "Ram out", "Ram in", and "Lock."

70 43 (Figs. 7, 8 and 9) denotes a lamp indicator adapted to work in conjunction with the indicator 42 whereby to indicate the movement of the ram, i. e. the positions intermediate the "full in" and "full out" positions.

75 When the mooring head is not in use, the pointer of the indicator 42 registers "Neutral"; in this position all the inlet valves 12-15 are closed and all the exhaust valves 16-19 are open. The indicator pointer is 80 adapted to make one revolution for each revolution of the cam spindle 30 and revolves in clockwise direction.

85 In operation, when the handwheel 34 is rotated in clockwise direction until the indicator registers "Unlock", pressure fluid is admitted to the cylinder of the locking piston whereby to withdraw it, thus leaving the ram element free to move. Further actuations of the control valve so that the indicator registers, successively, "Ram out", "Ram in", and "Lock" effects these operations by alternately admitting and exhausting the pressure fluid to and from the ram element and locking piston cylinders.

90 At the end of the sequence of operations, the handwheel 34 is rotated until the indicator registers "Neutral".

95 The operations of retracting the ram element and protruding the locking piston are 100 separated by a time interval so that the exhaust valve 19 for the underside of the ram element and the inlet valve 12 for the bottom of the locking piston have a distinctly 105 dead period when both valves are closed.

110 It will be understood that there is an idle period between any two succeeding operations when both the exhaust and inlet valves applying to that particular operation will be closed.

We claim:—

1. In combination with a mooring mast for a dirigible or the like, a control means having separate fluid passages and individual valves for each passage, and a control member for said control means having a number of pre-disposed cams thereon arranged to actuate the said valves in a predetermined sequence.

115 2. In combination, an airship mooring head having an arm secured thereto, means 120 to move said arm from one position to another, means to lock said arm in one of said positions, valves adapted to control each of said means, and a single control means to operate said valves in sequence to cause successive operation of said means.

125 3. In combination, an airship mooring head having an arm secured thereto, means to move said arm from one position to another, means to lock said arm in one of said 130

positions, a cam shaft adapted to operate said means in sequence, and means to rotate said shaft.

4. In combination, an airship mooring head having an arm secured thereto, means to move said arms from one position to another, means to lock said arm in one of said positions, valves adapted to control each of said means, a cam shaft adapted to operate said valves in sequence, to cause successive operation of said means, and means to rotate said shaft.

5. In combination, an airship mooring head having an arm secured thereto, means to lock said arm in one position, means to move said arm, and a single movable member adapted upon movement thereof to positively regulate successive unlocking of the arm, move it to another position and then back to initial position, and finally to again lock the arm.

6. In combination, an airship mooring head having an arm secured thereto, fluid pressure operated means for moving said arm axially, fluid pressure operated means for locking said arm in one position, valves adapted to control said means, and a single control means to operate said valves in sequence to cause successive operation of said means.

7. In combination, an airship mooring head having an arm secured thereto, fluid pressures operated means for moving said arm axially, fluid pressure operated means for locking said arm in one position, valves adapted to control said means, a cam shaft controlling the operation of said valves, and means to rotate said shaft.

40 ARCHIBALD HALL-BROWN.
EDWIN WALTER JONES.
